Norman Bel Geddes & Company, New York,
N. Y., a partnership

Application June 16, 1944, Serial No. 114,030

Term of patent 14 years

(Cl. D57—1)

To all whom it may concern:

Be it known that I, Nathaniel B. Wales, a citizen of the United States, residing at New York, in the county of New York and State of New York, have invented a new, original, and ornamental Design for a Film Viewer Casing, of which the following is a specification, reference being had to the accompanying drawing forming a part thereof, in which

Figure 1 is a perspective view of a film viewer

casing embodying my new design and showing the bottom of the device,

Figure 2 is an end view;
Figure 3 is a top view; and
Figure 4 is a front view.

I claim:

The ornamental design for a film viewer casing, as shown.

NATHANIEL B. WALES.
